ELECTRIC DISCHARGE DEVICE CIRCUIT

Matthew C. Abbott, Ipswich, Mass., assignor to
 Sylvania Electric Products Inc., a corporation
 of Massachusetts

Application February 6, 1942, Serial No. 429,793

4 Claims. (Cl. 315—138)

This invention relates to electric gaseous discharge lamps and in particular to apparatus for operating such lamps.

In the operation of fluorescent lamps, it is desirable that the stroboscopic effect be reduced to a minimum. The correction of this factor in three lamp circuits has been accomplished with improved results over that attained in two lamp circuits. However, this has been at the cost of considerable wattage loss due to resistance balance of the third lamp.

Therefore an object of my invention is to economically obtain operation of three lamps from a single phase circuit in a manner such that the light pulses, or stroboscopic effect, occur in turn at three equal intervals during each half cycle of the alternating current power source.

Another object of my invention is to provide adequate and economical starting circuits for said lamp operation.

A further object is the elimination of certain cathodes and the combining of three lamps so that three arcs may be sustained, each out of phase with the other, in the same atmosphere.

Still another object is the reducing of said combination to a compact area with substantially long arc paths but maintaining an equilibrium among said paths.

Other objects, advantages, and features will become apparent from the following specifications and accompanying drawings in which:

Figure 1 is a schematic diagram of the circuit of my invention;

Figure 2 is a vector diagram of the lamp light or currents as connected according to my invention demonstrating their phase relationship;

Figure 3 is a schematic diagram of a circuit which is a variation of that shown in Figure 1;

Figure 4 is another variation of said circuit as applied to an incorporated lamp;

Figure 5 is a schematic diagram of an application of the circuit shown in Figure 4.

In Figure 1 the circuit is connected to any suitable source of alternating current by the leads in wires 4 and 5 either through the auto-transformer 6 or directly thereto.

The circuit from leads 4 and 5 is completed through line 7, choke coil 8, cathode 18, switch 17, starting transformer primary 15 and cathode 22. Induced currents in the secondaries 13 and 14 of the starting transformer 16 heat cathodes 12, 19, 20 and 21 to the same temperature as cathodes 18 and 22. On initial opening or repeated openings of this circuit at switch 17, lagging arc discharge circuit 4, 7, 9, 18, 3, 19, 20, 2, 55

22, 5 and leading arc discharge circuit 4, 7, choke coil 8, condenser 10, 12, 1, 21, 20, 2, 22, 5 are established. The lagging circuit must be operated at a power factor of .5, i. e., 60 degrees, and the leading circuit must be operated at the same power factor so that the phase displacement of the two currents, one through arc 3 and one through arc 1, be 120 degrees. The current through arc 2 is the sum of the currents through arc 1 and arc 3.

As indicated in the vector diagram of Figure 2, the circuit currents must lead and lag by 60° each so that the magnitude of their vector sum is equal to either of the magnitudes of the two components. The currents flowing toward the joiner of the lamps will thus be 120 degrees apart electrically. The reactance of the condenser and choke in series with it, plus the reactance of the leading lamp itself, must be equal to the total reactance of the lagging circuit, within commercial tolerance. For best results the ratio of the condenser reactance to that of its series choke should be between 2.0 and 3.0 because values much less than this minimum result in high condenser voltages and have a deleterious effect on the uniformity of manufacture of the circuits because of the commercial condenser tolerances. Higher values will result in abnormal distortion of the current of this circuit. The reactance ratio increases with decrease of condenser reactance because the total reactance of the circuit is capacitive and constant so that the lamp current will be constant.

Figure 3 is a variation of the circuit in Figure 1. It shows how a current-operated switch may take the place of the voltage-operated switch. It also shows other means of facilitating starting by adding another delay switch 27 in series with electrode 12 and coil 13, and the additional 40 windings 23, 24 and 25 on the core. These windings are connected as in the diagram: winding 23 through a—a to cathode 18; winding 24 through c—c to cathode 12; and winding 25 to the cathode 22. Electrodes 19, 20 and 21 are connected to the winding 14 through b—b in the same manner as in Figure 1. The circuits of arcs 1 and 2 and of 2 and 3 are connected parallel so that either pair will continue to burn as one arc if the arc does not strike across the third 45 at the first start. Also by addition of the second delay starting switch the unlit arc is given another opportunity to strike.

Different switches may be used in starting these three lamp circuits such as using a current-operated thermal or magnetic element in series with

one lamp, the circuit-closing contacts being connected to the other two lamps.

Figure 4 is another variation of the circuit in Figure 1 in which the cathodes 19, 20 and 21 are dispensed with by joining the ends of all three lamps. An inert gas at low pressure and a small quantity of a metallic vapor may be sealed therein. In this circuit the leading current arc 1 and the lagging current arc 3 merge at point P and form the resultant arc 2 thus retaining the three phase lamp operation. The mercury vapor will generally be at low pressure, say 6 microns, when the lamp is operated.

As in Figures 3 and 4, if the line current is of satisfactory voltage, say 110 v., the leads 4 and 5 may be tapped direct to the line, thus eliminating the auto-transformer 6.

Another practical application of the advantages of the incorporated lamp may be visualized in Figure 5 in which the three lamps are contained in a single disc shaped envelope, in which 12, 22 and 18 are the filamentary electrodes placed in the centermost of several concentric channels which are divided by the partitions 28, 29, and 30 to form equal length paths for each arc, 1 being the leading arc, 2 the resultant arc, and 3 the lagging arc. By this means the longest possible arc paths are contained in a compact form. Because point P must be equi-distant along the arc paths from all the filamentary electrodes, the angles θ_1 , θ_2 , and θ_3 between the partitions become very critical. They must be substantially 60°, 120° and 180°, for uniformity in length of the arc paths.

What I claim is:

1. A circuit for the operation of three-arc discharges of equal magnitude in electrical gaseous discharge devices having at least three electrodes and in which there is present a leading current arc discharge component, a lagging current arc discharge component, and an arc discharge current in resultant phase with respect to said leading and lagging currents; said circuit including: an inductive impedance ballast for the lagging current arc discharge component; a capacitive impedance ballast for the leading current arc discharge component; and an arrangement for producing said resultant phase arc discharge; said arrangement comprising a combination of said inductive and capacity impedances such as to displace the arc discharge current components from each other so that the magnitude of their vector sum is equal to either of the magnitudes of the two components, whereby said resultant phase arc discharge is controlled jointly by the current of said leading and lagging arc discharge components.

2. A circuit for the operation of three-arc dis-

charges of equal magnitude in electric gaseous discharge devices having at least three electrodes and in which there is present a leading current arc discharge, a lagging current arc discharge, and an arc discharge current in resultant phase with respect to said leading and lagging currents, said circuit including: an inductive impedance electrically connected between one of said electrodes and one side of the line voltage; a second inductive impedance and a capacitive impedance in series, electrically connected between a second of said electrodes and said side of the line voltage; and a combination, comprising said first inductive impedance in parallel with said series arrangement of said second inductive impedance and said capacitive impedance, electrically connected between a third of said electrodes and said side of the line voltage.

3. A circuit for the operation of three-arc discharges of equal magnitude in electric gaseous discharge devices having at least three electrodes and in which there is present a leading current arc discharge, a lagging current arc discharge, and an arc discharge current in resultant phase with respect to said leading and lagging currents, said circuit including: an inductive impedance electrically connected between one of said electrodes and one side of the line voltage; a second inductive impedance and a capacitive impedance in series, electrically connected between a second of said electrodes and said side of the line voltage; and a combination, comprising said first inductive impedance in parallel with said series arrangement of said second inductive impedance and said capacitive impedance, electrically connected between a third of said electrodes and said side of the line voltage; with the ratio of the reactances of said capacitive impedance and said second inductive impedance in series therewith being between 2.5 and 3.0.

4. An electric gaseous discharge lamp for three arc discharge operation, said lamp comprising: an envelope having a plurality of partitions in maze-like arrangement; three electrodes mounted centrally of said maze-like arrangements centrally separated from each other by certain of said partitions, and accessible to each other through traverse of said maze; said maze-like arrangement being such as to form paths for three joining arc discharges with said electrodes as terminals; and means for passing electric currents in each of said paths between said electrodes, said currents being displaced from each other so that the resultant of any two of the currents is vectorially equal to and opposite the other.

MATTHEW C. ABBOTT.
